UNITED STATES PATENT OFFICE.

ALBERT J. McCUALEY, OF ST. LOUIS, MISSOURI, ASSIGNOR TO AMERICAN CAR & FOUNDRY COMPANY, OF ST. LOUIS, MISSOURI, A CORPORATION OF NEW JERSEY.

TANK-CAR.

No. 861,474.

Specification of Letters Patent.

Patented July 30, 1907.

Application filed March 5, 1907. Serial No. 360,652.

To all whom it may concern:

Be it known that I, ALBERT J. McCUALEY, a citizen of the United States, residing at St. Louis, Missouri, have invented a certain new and useful Improvement 5 in Tank-Cars, of which the following is a full, clear, and exact description, such as will enable others skilled in the art to which it appertains to make and use the same, reference being had to the accompanying drawings, forming part of this specification, in which—
10 Figure 1 is a side elevational view, partly in section, of my improved tank car; Fig. 2 is a sectional view taken on the line 2—2 of Fig. 1; Fig. 3 is a plan view of the interlocking members that prevent the tank from shifting independently of the underframe; and
15 Fig. 4 is a perspective view of one of the members shown in Fig. 3.

This invention relates to new and useful improvements in tank cars.

The object of my invention is to provide a tank car 20 in which the tank is secured to an underframe by means which allow the tank to expand independently of the underframe.

Another object is to provide a tank car in which the tank is interlocked with an underframe by means 25 of adjustable interlocking members.

In the preferred form of my invention the tank and underframe are provided with lugs or projections which interlock and prevent the tank from shifting longitudinally independently of the underframe. The 30 tank projections normally engage the underframe projections, but said tank projections are free to move with the tank when it expands. The tank is prevented from rolling preferably by means of bands, which are secured to the underframe and extend over the tank.

35 Referring to the drawings, the underframe comprises body bolsters located near the ends of the car and secured to longitudinal sills 1. Buffer blocks 2 riveted to the ends of the longitudinal sills are adapted to receive suitable drawbars.

40 The body bolsters herein shown are built up of flanged diaphragms 3 which extend outwardly from the longitudinal sills; said diaphragms being connected by a channel 4 arranged above the longitudinal sills, and a plate 5 below said sills. Center bearings 6 are 45 secured to the underside of the body bolsters, and filler blocks 7 are interposed between the longitudinal sills above the center bearings.

50 The tank rests on wood blocks 8 which are secured to the curved top portions of the body bolsters. A tank-supporting member 9 is secured to the underframe at the center of the car. Bands 10 are secured to the body bolsters and extend over the tank. Straps 11 extend under the longitudinal sills and are connected

by turnbuckles 12 to the lower end of bands 13, the upper ends of said bands being connected to curved rods 14 which surround the tank dome 15.

Curved sheets 16 form the top and side walls of the tank, the bottom of the tank being formed by a sheet 17 which is preferably continuous from end to end of the tank.

60

18 indicates the usual tank heads.

Lugs 19 are riveted to the bottom tank sheet 17 adjacent the ends of the tank. 20 indicates lugs which are secured to the longitudinal sills. These lugs 20 are located between and normally engage the lugs 19. 65 This arrangement of the lugs 19 and 20 provides abutments which prevent the tank from shifting longitudinally independently of the underframe, and said abutments allow the tank to expand since the lugs 19 are free to move with the tank when it expands. The 70 lugs or abutments 20 preferably comprise flanges 21 which are riveted to the longitudinal sills and a vertical wall 22 which is reinforced by webs 23.

24 indicates wedges which I have herein shown as forming part of the abutments 20, said wedges preferably having an integral dove-tail shaped portion 25 that is located in a correspondingly shaped recess formed in the wall 22. If desired, the dove-tail portion of the wedge and its corresponding recess may be omitted. The wall 22 would then form the underframe 80 abutment, and the wedge 24 would be interposed between the co-operating abutments of the tank and underframe.

When the tank is mounted on the underframe the wedges are adjusted to engage the tank projections 19 85 and are locked in their adjusted position by means of split keys 26 which are adapted to pass through any one of the holes 27 in the wedges. The keys 26 engage the outer face of one of the webs 23 and thereby retain the wedge in position.

90 If the relative position of abutments 19 and 20 was not adjustable it would require accurate fitting to locate these members so that they would normally engage each other, and if said members did not engage each other the severe stresses to which the car is subjected would cause injurious shocks at this point.

While I have herein shown a means for adjusting the relative position of the abutments comprising a wedge and a key for locking said wedge in position, my invention is not limited to this exact construction, as 100 various modifications from the design herein shown will suggest themselves to those skilled in the art.

Having thus described the invention, what is claimed as new and desired to be secured by Letters Patent is:

1. In a tank car, the combination with a tank, of a 105 frame, and members carried by the tank which are free

- to move with the tank when it expands, said members being normally in engagement with abutments on the underframe; substantially as described.
2. In a tank car, the combination with a tank, of an underframe, members secured to the tank which normally engage members secured to the underframe, said members forming abutments that prevent the tank from shifting longitudinally, the members which are secured to the tank being free to move with the tank when it expands; substantially as described.
3. In a tank car, the combination with a tank, of an underframe, lugs secured to the tank which normally engage lugs secured to the underframe, said lugs forming abutments that prevent the tank from shifting longitudinally, the lugs which are secured to the tank being free to move with the tank when it expands; substantially as described.
4. In a tank car, the combination with a tank, of an underframe, lugs secured to the tank, which lugs normally engage lugs secured to the underframe, the lugs that are secured to the tank being free to move when the tank expands; substantially as described.
5. In a tank car, the combination with a tank, of an underframe, interlocking members forming abutments that prevent the tank from shifting longitudinally, the relative position of said interlocking members being adjustable; substantially as described.
6. In a tank car, the combination with a tank, of an underframe, interlocking members forming abutments that prevent the tank from shifting longitudinally, the relative position of said interlocking members being adjustable, and means for locking said interlocking members in their adjusted position; substantially as described.
7. In a tank car, the combination with a tank, of an underframe, interlocking members forming abutments that prevent the tank from shifting longitudinally, means for adjusting the position of one of said abutments, and means for locking said abutment in its adjusted position; substantially as described.
8. In a tank car, the combination with a tank, of an underframe, lugs secured to said tank and underframe, said lugs forming abutments that prevent the tank from shifting longitudinally, and means for independently adjusting the position of one of said abutments; substantially as described.
9. In a tank car, the combination with a tank, of an underframe, lugs secured to said tank and underframe, said lugs forming abutments that prevent the tank from shifting longitudinally, means for adjusting the relative position of said abutments, and means for locking said abutments in their adjusted position; substantially as described.
10. In a tank car, the combination with a tank, of an underframe, co-operating abutments secured to said tank and underframe, and an adjustable member interposed between said abutments; substantially as described.
11. In a tank car, the combination with a tank, of an underframe, co-operating abutments secured to said tank and underframe, an adjustable member interposed between said abutments, and means for locking said member in its adjusted position; substantially as described.
12. In a tank car, the combination with a tank, of an underframe, co-operating abutments secured to said tank and underframe, and an adjustable wedge interposed between said abutments; substantially as described.
13. In a tank car, the combination with a tank, of an underframe, co-operating abutments secured to said tank and underframe, an adjustable wedge interposed between said abutments, and means for locking said wedge in its adjusted position; substantially as described.
14. In a tank car, the combination with a tank, of an underframe and abutments secured to the tank which normally engage abutments secured to the underframe, the underframe abutments being arranged between the tank abutments, substantially as described.

In testimony whereof I hereunto affix my signature in the presence of two witnesses, this second day of March 1907.

ALBERT J. McCUALEY.
